UNITED STATES PATENT OFFICE.

ALFRED LUBAC, OF PARIS, FRANCE.

MACHINE FOR COMPOSING AND JUSTIFYING LINES OF PRINTING TYPES.

Application filed March 29, 1923. Serial No. 628,503.

To all whom it may concern:

Be it known that I, ALFRED LUBAC, a citizen of France, and a resident of Paris, France, have invented some new and useful 5 Improvements in Machines for Composing and Justifying Lines of Printing Types, of which the following is a specification.

The invention relates to machines for composing and justifying of lines of printing 10 types and its object is to provide a machine of composing working with channels and a key board effecting mechanically the justifying of the lines, the ejection system and the form of the channels assuring the normal descent of the types the forwarding 15 device being a single plane inclined and uncovered.

The mechanical composition of the printing types could never be realized in a manner to present real advantages over the manual composition. In the machines with channels the system of ejection and forwarding of the types were too complicated to permit a regular working, especially in case of a 20 plurality of ranges or rows of the channels. When utilizing the inclined channels, the eye of the types descended more rapidly than the foot and the column of the types leaned, rendering thereby impossible the ejection. 25 Finally, the mechanical justification of the lines was an impediment never to be surmounted.

The channels are, according to the present invention, disposed in several rows. 30 They are perpendicular to the inclined plane serving as slide for the ejected types.

The composition is effected by pressing upon the keys actuating the ejectors by means of tringles and the justification is 35 operated by means of devices described in the French Patents Nos. 510,343 and 521,182 of the applicant, by shifting the lines by means of a rake below a searcher of spaces, the tooth whereof abuts against the types 40 permits passage of words and falls in the special notch of spaces in order to open an interval between the words.

In the drawings annexed to the present specification:

50 Fig. 1 is a lateral view of the machine, without feet,

Fig. 2 represents, in an enlarged scale, the lower part of a channel, in a side view, in position upon the slide above an ejector;

55 Fig. 3 represents the lower part of three channels in position upon the slide with

their ejectors, seen from the back, according to a section A—A of Fig. 5;

Fig. 4 is an elevation of the lower part of a channel seen from the opposite side to the Fig. 2, and a view from the top, of the channel;

Fig. 5 is a frontal view of the plan showing a part the ejectors from above; in openings provided in the slide, the channels above the openings and the plates guiding the ejected types;

The Figures 6 and 6bis represent the plane view of the machine, the slide being supposed horizontally; these two figures being joined according to lines X—X;

Fig. 7 is a plane view of a plate;

Fig. 8 is a section according to B—B of Fig. 5;

Fig. 9 is a section according to C—C of Fig. 6bis;

Fig. 10 is a section according to D—D of Fig. 6bis;

Fig. 11 represents the rake seen from above;

Fig. 12 is a section F—F seen from the right of Fig. 6bis of F up to line E—E;

Fig. 13 is a detail view, and

Fig. 14 is the revolving pallet seen from above.

With regard to Figs. 1 to 6, the position of the channels 1 is assured by cuts provided in angle irons 2, of steel, supported at each end by pillars 3 of cast iron. The angle irons supporting the channels in the upper part, are fixed above the pillars; the lower angle irons are fixed upon angle irons 4 applied against the pillars, from within. 90

The bottom of the channels is convex in order to facilitate the sliding of the types. They are fitted in the lower part with a heel 5 serving as their support upon the slide 6. The one of the borders is prolonged by a projection 7 bent inwardly in a right angle in a manner to form a sole 8 supporting the column of types when the channels are not in position upon the machine. 100

When the channels are in position, they are situated above an ejector 9 projecting a little beyond an opening 10 provided in the plate of the inclined plane forming the slide. The ejector is provided with a broad slit 11 (Fig. 2) in the upper part. Its fixation is effected by means of or rather at an end of a tringle 12 carrying a key 13 at the other 110 end and permitting of being swung into holes of two angle irons 14 and 15 extending

the whole width of the machine and having their ends lodged in the slits of two bands 16 in cast iron or steel reposing upon the framing 17.

5 At each side of the slit 11 of the ejector a flat portion in the upper part is provided forming two soles 18 supporting the type column in case that the channel is in position having its sole engaged in the slit 10 of the ejector.

The ejector is maintained in a vertical plan by a spring 19. When a key is pressed it oscillates and the type touching the soles is pushed beyond the channel by two claws 15 20 projecting a little beyond the soles of the ejector. The ejector having accomplished its first oscillation, the type column is supported by the claws. At the back oscillation, the type column descends in order to 20 place itself upon the soles. The amplitude of the oscillations of the ejector is limited by the borders of the opening wherein it engages.

The ejection of the types is effected at the 25 side of the channels, opposed to the projection. This side bent outwardly in a right angle, forms a wing 21 impeding the type from turning backwardly at its exit from the channel. The interval between the 30 soles of the ejector and the wing is sufficient to let pass a type, but one type only.

On leaving the channel the type is placed flat on the side. It is guided firstly between the borders of two plates or the like 22.

35 If arriving from a superior channel, it passes above the openings disposed below, as shown in Fig. 5, follows thereupon the oblique flanges 23 directing the broad types of usual width against a channel 24 and the 40 broad types against another channel 25.

The two channels abut in the same point upon the radius of assembling of the types. While falling upon the channels the types arrange themselves edgewise before passing 45 upon the assembling spot.

The two channels are necessary for placing edgewise of the types. The channel of the ordinary types must have a width sufficient to permit the falling of the types 50 into the same while resting edgewise. The same ought not to be so wide as to permit the types of placing themselves flat. This is the reason why a special channel is necessary for wide or broad types.

55 The channel for wide types of ordinary width is formed by the point of the slide 26 which is the one side thereof, by the ledge 27 which is the other side and by the assembling and justifying platform 28 60 which constitutes the bottom of the channel. The ledge 27 is fixed upon the platform 28 which is lower than the slide whereof the triangle point advances upon the platform 28.

65 In arriving upon the assembling ray, the

types are arrested by a ledge 30. They are shifted in line by a double pallet 31 rotating between the branches of a measuring slide 32 immovable during the composition.

The pallet 31 is fixed at the end of an 70 axle carrying a pulley 33 against the other end, below the platform 28. The end of the axle pivots in a bearing carried by a rod 34 serving also for assembling of the 75 machine walls.

The machine represented in the drawings in the way of an example shows three rows 80 of channels. The upper channel, well visible and easily to be put in place or to be taken away, are reserved for types used most frequently. The keys corresponding to these channels are grouped in the lower part of the key board.

The keys corresponding to the two other rows of channels are not grouped. They 85 extend themselves upon the whole width of the machine and form the two first ranges of the key board.

The keys of the three first ranges of the key board, beginning from the top, command the ejectors with aid of a sole tringle. The keys of the fourth and fifth range command the ejectors of sixteen channels of the left of the uppermost range with aid of two tringles each one of them 90 carrying a lever in its lower part. There is a tringle for the key and a tringle for the ejector. The two tringles are rendered solidary by a third tringle 35 articulated with the two levers. Upon Fig. 1 are represented two levers 36 on the tringles of the keys of the fourth range and two levers 37 on the tringles of the keys of the fifth range.

The tringles of the eight keys of the 105 fourth range are carried by the rod 38 and by the rod 39. The tringles of the eight keys of the fifth range are carried by the rod 38 and by the rod 40.

When commencing a line, the first type 110 applies itself against the pallet of a rake 41 carried by a body having as its guide the ledge 30 raised in order to serve as a rail for the same. In proportion as the types arrive, the rake moves away from the rotating pallet. The pallet of the rake is slit in a manner to pass below the space 115 searcher without touching the same.

When the composition represents nearly 120 the length of a line, the same is measured by shifting to the left the needle 42 solid with a tooth wheel 43 engaging a rack 44 forming part of a slide having two branches, the assembling pallet rotating between the latter. The slide shifts the composition to 125 the right when the needle is shifted to the left. At the same time when shifting the needle for measuring the composition, the abutment 45 is lowered by pressing upon the same with the finger, this abutment serving 130

then as stop for the rake. The line is then squeezed between the slide and the rake. The needle indicates upon a graduated sector 46 the difference between the measured 5 length and the length which the line ought to have.

The rake is brought thereupon to the other end of the line.

In order to justify a line, firstly the necessary 10 spaces are fed into the collecting channel of the spaces of justification 47 where they are united flat wise end to end, the first thereof being in front of a pallet 48. The justification is operated in making pass 15 the line, by means of the rake 41, below a space searcher 49, with aid of means described in the French Patents Nos. 510,343 and 521,182 of the applicant.

The elements of the justifying apparatus 20 are represented in Fig. 6 in order to show the position they occupy in the machine. No description is given of these elements, no claims being established for the same.

After justification of the line the same 25 is shifted to the right with the rake 41 until it is arrested by the ledge 50 surpassing the line of the ledge 30 and slit slightly in its lower part. The finger describes a fourth of a circle on the line in order to place the 30 same upon a shutter 51 which can be raised by means of a lever 52. The line arriving upon the shutter, the pallet 53 is disposed against the lines composed as shown in dotted lines in Fig. 12. The pallet is carried 35 by a rod 54 the pivotal ends whereof can slide in two bearings 55, 56. In order to pass the pallet behind the line disposed upon the shutter, the line is raised by applying the finger to the pin 57 and shifting 40 the line to the left. The shutter is lifted thereupon in order to apply the line against the pallet, whereupon the shutter is left to fall back, the line being shifted thereupon to the right with the pallet.

What I claim, is:

1. In a machine for composing and justifying the lines of the printing types, several ranges of channels with convex bottoms, a supporting heel in their lower part, a sole in the same for supporting the types when 50 the channels are not in position, and a wing in the same, for impeding the types from falling back during ejection, and means to arrange the channels perpendicularly to a single inclined plane serving as slide.

2. In a machine for composing and justifying the lines of the printing types, several ranges of channels with convex bottoms, a supporting heel in their lower part, a sole in the same for supporting the types when 60 the channels are not in position, a wing in the channels for impeding the types from turning backwardly when being ejected, the arrangement of the channels perpendicularly to a single inclined plane serving as their slide, ejectors with soles, claws and slits fixed at the end of a tringle carrying a key at the other end, oscillating owing to the action of the key and of a counteracting spring between the borders of an opening in the plate of the inclined plane forming the slide.

3. In a machine as described and claimed, a slide constituted by a plane of metal with openings wherein oscillate ejectors; type 75 channels wherein types may slide above the ejectors, plates and ledge guiding the ordinary types against a special channel, the wide types against another channel having the same issue as the first one and the spaces 80 of justification against another channel.

4. In a machine as claimed in claim 2, an assembling device for the lines comprising a shutter for redressing of the lines and a pallet carried by a rod sliding in two 85 bearings.

In witness whereof I affix my signature.

ALFRED LUBAC.
